(57) **CLAIM**

The ornamental design for a bottle opener incorporating a slotted shaft for housing screwdriver bits, as shown and described.

DESCRIPTION

FIG. 1 is a top perspective view of a bottle opener incorporating a slotted shaft for housing screwdriver bits;

FIG. 2 is a top plan view thereof, to bottom plan view being a mirror image thereof;

FIG. 3 is a front elevation view thereof, the rear elevation view being a mirror image thereof;

FIG. 4 is a left side elevation view thereof; and,

FIG. 5 is a right side elevation view thereof.

The broken lines showing a double-ended screwdriver bit depict environmental subject matter only and form no part of the claimed design.
